UNITED STATES PATENT OFFICE.

EGBERT L. MARANVILLE, OF RUTLAND, VERMONT.

MECHANICAL MOVEMENT FOR CHURNS.

SPECIFICATION forming part of Letters Patent No. 258,238, dated May 23, 1882.

Application filed February 11, 1882. (No model.)

To all whom it may concern:

Be it known that I, EGBERT L. MARANVILLE, a citizen of the United States of America, residing at Rutland, in the county of Rutland and State of Vermont, have invented certain new and useful Improvements in Mechanical Movements for Churns; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a perspective of my invention; Fig. 2, a detail in perspective; Fig. 3, an end elevation; and Fig. 4, a side elevation, showing also in dotted lines the positions assumed by different parts of the mechanism employed at different extremes of the movement thereof.

Like letters refer to like parts in all the figures.

My invention relates to the means employed for producing an oscillatory movement in or of the body of a churn; and it consists in certain devices and combinations of devices, hereinafter more fully described, and specifically set forth in the claims.

30 A A represent the side frames, and B B the tie-rods, of a suitable supporting structure upon and within which the body G of a churn is secured and operated. One of the frames A is provided with an upright standard, C, on which, externally, at c, is pivotally supported the main operating-lever D, which at its lower end is provided with a pin, d, extending through a slot, e, in the lower end of a secondary operating-lever, E, located inside of 35 the frame, and provided with a bearing, e', through which the upper tie-rod B passes, and with diagonally-disposed supporting-straps e² e², bent to form supports e² e³ for the body of the churn, as clearly shown in Fig. 3. The lever E is also perforated at e⁴ for the reception 40 of a pin, f, on the free end of a spring-catch, F, secured to the body of the churn. Similar diagonal supporting-straps, e² e³, provided with

a bearing like e', are suitably secured to the opposite side of the body of the churn, said bearing being occupied by the upper cross-bar B, as clearly shown in Fig. 3.

The churn-body is provided with a discharge-opening, h, and a removable cover, I, secured by buttons i i.

The operation of my invention is as follows: Swinging the upper end of lever D to the right, Figs. 1 and 4, throws its lower end to the left, and carries with said lower end the lower end of lever E, the pin d riding up the slot e. 60 This movement throws the body of the churn to the right and slanted, as shown in said Fig. 4. A reversal of the movement of lever D throws the churn to the right, also shown in dotted lines.

The supporting-straps upon the back of the body may be secured thereto removably by a spring-catch, F, as are those on the front; or they may be permanently attached by screws, and the bearing thereof be open or of Ω shape, 70 and thus adapted to rest upon the upper tie-rod, B, and easily removable therefrom, when, to remove the body from the movement and frame-work, the spring-catch F is lifted from lever E, and the body lifted directly from said lever and the frame-work.

It will be noticed that sudden and forcible agitation of the contents of the churn is accomplished with a smooth movement of the mechanism and the body about their supporting-pivots, and with slight exertion on the part of the operator.

It is evident that either of the levers D or E may be slotted, and that one which is not slotted may carry the pin d, and in some cases it 85 may be desirable that lever E should carry the pin d and lever D be slotted.

Having described my invention and its operation, what I claim as new, and wish to secure by Letters Patent, is—

1. The combination of the frame A, lever D, pivoted thereto, and provided with the pin d, with the slotted lever E, pivoted inside of the frame to the cross-bar B, and adapted to support the body G of a churn, substantially as 95 shown and described.

2. The combination of levers D and E, located outside and inside of the frame, respectively, frames A A, and cross-bar B, with the body G of a churn, provided with the spring-catch F, substantially as shown and described.

5 3. The lever E, slotted at e, and provided with the bearing e' and supporting-straps e² e³, in combination with the churn-body G and

means for its oscillation upon the cross-bar B, substantially as shown and described.

In testimony whereof I affix my signature in presence of two witnesses.

EGBERT L. MARANVILLE.
